H. G. FIELD.

ROTARY VALVE FOR INTERNAL COMBUSTION ENGINES.

APPLICATION FILED OCT. 25, 1915.

1,253,364.

Patented Jan. 15, 1918.

UNITED STATES PATENT OFFICE.

HARDIN G. FIELD, OF DENVER, COLORADO.

ROTARY VALVE FOR INTERNAL-COMBUSTION ENGINES.

1,253,364.

Specification of Letters Patent. Patented Jan. 15, 1918.

Application filed October 25, 1915. Serial No. 57,754.

To all whom it may concern:

Be it known that I, HARDIN G. FIELD, a citizen of the United States of America, residing at the city and county of Denver and 5 State of Colorado, have invented a new and useful Improvement in Rotary Valves for Internal-Combustion Engines, of which the following is a specification.

My invention relates to improvements in 10 rotary valves for controlling the intake and exhaust ports of internal combustion engines.

The object of the invention is to provide a ported rotary valve which can be employed in connection with a single cylinder, or with two or more cylinders positioned in a direct line as in automobile engines, the ports in said valve being arranged to admit explosive mixture to, and permit the escape 20 of the exploded gas from the cylinders in predetermined order.

A further object of the invention is to provide a single piece, cylindrical, rotary valve provided with an intake and an exhaust port for each cylinder employed, said ports being in predetermined order, such construction eliminating the multiplicity of valves and their operating mechanism in common use, together with the greater wear 25 and necessary repair consequent thereto, said valve being driven from the engine crank shaft, and arranged to make one rotation to every two rotations of the said crank shaft.

These objects are accomplished by the mechanism illustrated in the accompanying drawings, in which:

Figure 1, is a vertical, longitudinal sectional view of a four cylinder automobile 40 engine constructed in accordance with my invention.

Fig. 2, is a vertical, transverse sectional view through one of the cylinders on the line of the exhaust port of the valve, and 45 showing the valve in the position it assumes at the instant it closes the exhaust.

Fig. 3, is a similar sectional view on the line of one of the intake ports, the valve being in the position it assumes at the beginning of the intake stroke of the piston.

Fig. 4, is a horizontal, sectional view on the line 4—4 of Fig. 3, and on a smaller scale, illustrating the arrangement of the intake and exhaust passages. And

Fig. 5 is a horizontal, sectional view on the line 5—5 of Fig. 3.

Similar letters of reference refer to similar parts throughout the several views.

In the common type of automobile engines, the inlet and exhaust of each cylinder 60 is controlled by two puppet valves, which are actuated to open their respective ports by a cam shaft, and are thrown to close their ports by springs. This construction necessitates the employment of eight valves 65 for a four cylinder engine, together with a cam shaft and its driving mechanism, which mechanism comprises a great number of parts that must be accurately constructed, and which require care and frequent repair 70 to maintain them in a condition which will enable the engine to develop the highest efficiency. The present invention is designed to eliminate a multiplicity of parts in the valve construction and operation by the substitution of a single valve adapted to control the inlet and exhaust ports of all the cylinders constituting the engine, as will be hereinafter set forth.

Referring to the accompanying drawings,—

The numeral 1 indicates the cylinders of a four cylinder, internal combustion engine, such as is commonly used in connection with automobiles. 2 indicates the pistons, which 85 are connected by piston rods 3, with a crank shaft 4, all of which parts are of a style in common use. Each cylinder is provided with a transverse slot 5, in its upper end, which serves both for an intake and an exhaust port, and these ports open out into a longitudinal, semi-circular bearing recess 6, which is formed in the engine casing immediately above the tops of the cylinders, and forms one half part of the bearing for 90 the improved rotary valve 7, which extends above the tops of all of the cylinders constituting the engine, and terminates at its ends in slightly reduced stems 8, which extend beyond the ends of the engine casing. 100

The cylinders are water-jacketed in the usual manner, as shown at 9, and a similarly water jacketed cap 10 is secured upon the top of the engine casing, and is formed with a longitudinal, semi-circular recess 11, 105 which matches the recess 6 in the engine casing, and forms the other half part of the bearing for the rotary valve. The cap 10 is formed with intake and exhaust chambers 12 and 12^A and 13 and 13^A respectively, which are connected by passages 14 and 15 respectively, with intake and exhaust

pipes 16 and 17 respectively, which may be of any commonly employed type.

The valve 7 comprises a tubular, cylindrical shaft, the peripheral surface of which is provided with semi-circular ports so arranged that two of these ports are adapted to register with the slot or port 5, in each of the cylinders; therefore, in a four cylinder engine as shown, the valve 7 would be provided with eight ports which are arranged with respect to the order in which the cylinders are fired.

In the present illustration, the cylinders will fire in the order of 1, 3, 4, 2, the piston of the first cylinder being at the limit of the exhaust stroke, that of the last cylinder being at the limit of the compression stroke, while the pistons of the second and third cylinders are respectively at the limit of the intake and explosion strokes. The intake valve ports 18 and 19 for the first and second cylinders respectively, adjoin, but are not in the same direct line; likewise the intake valve ports 20 and 21 for the third and fourth cylinders respectively adjoin, but are not in the same direct line; the exhaust ports 22 and 23 for the first and fourth cylinders are at the respective ends of the valve and out of direct line, and the exhaust ports 24 and 25 of the second and third cylinders adjoin and are also out of direct line. The intake valve ports 18 and 19 for the first and second cylinders respectively, register with passages 25^A and 26 respectively, which communicate with the intake chamber 12. The valve intake ports 20 and 21 for the third and fourth cylinders register respectively with passages 27 and 28, which communicate with the intake chamber 12^A. The exhaust ports 22 and 24 for the first and second cylinders register with passages 29 and 30 respectively, which communicate with the exhaust chamber 13; while the exhaust ports 25 and 23 of the third and fourth cylinders respectively, register with passages 31 and 32 which communicate with the exhaust chamber 13^A. Thus it will be seen that as the valve 7 rotates, its intake ports are timed to admit explosive mixture to the cylinders in the order above stated, and likewise the exhaust ports are correspondingly timed. One end of the valve 7 may be provided with a sprocket wheel 33, which is driven by a chain, from a sprocket wheel 34 on the crank shaft, the latter wheel being one-half the diameter of the wheel 33, so that two complete rotations of the crank shaft produce one rotation of the valve.

While I have illustrated a sprocket and chain connection between the crank shaft

and valve, the same result may be accomplished by connecting the said valve and crank shaft by gearing in such manner as to effect a single rotation of the valve for every two rotations of the crank shaft.

The valve is provided with a plurality of oil holes 35, which form a communication between its interior and its outer peripheral surface, these holes being preferably located along annular paths between the lines of the ends of the ports in said valve. The valve may be filled with oil conveyed in any suitable manner from the crank case, or it may be charged manually from one end; and as the valve rotates, the oil feeds out through the holes 35, and thus keeps the bearing surface of the valve thoroughly lubricated. The bearings at each end of the valve are likewise furnished with oil.

The edge 36 of the valve bearing 6, forms a cut-off both for the exhaust and for the inlet ports of the valve as, when each valve port passes this lip, communication between the cylinder and either the intake or exhaust manifold is closed, as will be understood by reference to Figs. 2 and 3.

In operation, the valve is rotated from the crank shaft in the manner above described, the ports being timed to admit explosive mixture to the cylinders in predetermined order, and to permit the exploded gas to exhaust in corresponding order.

Having described my invention, what I claim as new and desire to secure by Letters Patent is:

An engine casing having a plurality of cylinders, and a cylindrical passage which extends through the casing above the cylinders, each cylinder being provided with a common inlet and exhaust port opening into said passage, a housing formed in said casing above said passage, which is divided centrally of its length and centrally of its width to form an inlet and exhaust chamber for each pair of cylinders, said chambers being connected with said passage and with inlet and exhaust pipes, and a rotary cylindrical valve in said passage having peripheral inlet and exhaust ports which communicate respectively with the inlet and exhaust chambers for each pair of cylinders, and with the common inlet and exhaust cylinder ports, and means for rotating said valve.

In testimony whereof I affix my signature in presence of two witnesses.

HARDIN G. FIELD.
